UNITED STATES PATENT OFFICE.

DAVID G. RULON, OF MONMOUTH, ILLINOIS.

HANGER FOR PICTURE OR MIRROR FRAMES.

SPECIFICATION forming part of Letters Patent No. 449,496, dated March 31, 1891.

Application filed November 8, 1890. Serial No. 370,805. (No model.)

To all whom it may concern:

Be it known that I, DAVID G. RULON, of Monmouth, in the county of Warren and State of Illinois, have invented a new and useful 5 Hanger for Picture or Mirror Frames, of which the following is a full, clear, and exact description.

The objects of this invention are to provide a simple, convenient, and inexpensive device 10 that may be quickly attached to mirror or picture frames of different sizes and afford means to suspend the frame from a wall and incline it therefrom at any desired angle.

To these ends my invention consists in the 15 peculiar construction and combination of parts, as is hereinafter described and claimed.

Reference is to be made to the accompanying drawing, forming a part of this specification, and to the letters of reference marked 20 thereon.

The figure of the drawing exhibits in perspective the complete device in connection with the rear side of a frame of ordinary construction, and adjusted to suspend the frame 25 from a hook or nail in a vertical wall and incline said frame at a desired angle.

The device is adapted to be removably attached to the rear side of a frame A, as shown in the drawing; and it consists, essentially, 30 of wire rods bent into form, as will be more fully described.

The suspending clasp B is formed from a single piece of wire, which is bent near its center of length to produce an eye a and then 35 outwardly and upwardly, affording two parallel limbs b, which at b' are coiled around a horizontal stay-rod C, and thence upwardly extended. The eyes c are formed on the limbs b at a proper distance above the rod C and 40 near these eyes a series of return-bends are produced on each limb that form ratchet-racks d, above which the hooks e are formed on the terminal ends of said limbs b. A spiral spring D is secured by a hook formed on one 45 end to the eye a and at its opposite end in like manner to the upper looped end f of a link E, the lower end of said link having a looped engagement with a hook piece or clasp F, which is bent from a single piece of 50 wire, so as to afford an eye g, to which the link E is attached, and two limbs, which are

spread apart, as shown, and terminate in hooks h, that are bent in the same direction.

Upon the end portions of the stay-bar C, that project beyond the coils b' of the limbs

b, the ends of a wire prop-piece G are wrapped and then secured to the limbs b, said prop-piece preferably consisting of a wire rod bent at i i to produce a cross-bar k and two limbs m, that are connected with the stay-bar and 60 limbs b, as stated. At points equally distant from the corners i on the prop-piece G ring-eyes n are formed in the limbs m. The eyes n are loosely engaged by the trunnion ends o, which are oppositely projected from and are 65 the terminals of a rocking brace H, that projects from the prop-piece G toward the ratchet-racks d. The brace H consists of a wire rod bent twice at essentially right angles to form the cross-bar o' and limbs o², the ends 70 of which are bent to form the trunnions o. The cross-bar o' of the brace is adapted to engage opposite teeth of the racks and hold the prop-piece inclined outwardly from the frame A, the adjustment of the brace H upon the 75 racks d giving different degrees of angular projection to the prop-piece G.

A strand of wire I is provided for the suspension of the entire device, which is connected by its ends to the eyes c, said strand 80 being doubled at p, where it may be hung upon a hook or nail in a wall and retain the frame A suspended therefrom, when the hanger device is secured to the frame. This is preferably effected by expanding the spring 85 D and hooking the hooks e h upon the ledges A', that are provided on a large proportion of frames as ordinarily manufactured. When the ledges A' are omitted from a frame, the holder-wires s may be utilized to retain the 90 hanger in connection with the frame A, said wires being fastened at their ends to knobs s', which are attached to the frame, so that an extension of the spring D will allow the hooks e h to catch upon the holder-wire strips 95 s and fasten the hanger on the frame which is to be suspended.

By providing a few different sizes of the improved hanger a large range in size and weight of picture or mirror frames may be 100 safely and expeditiously connected therewith, and in case the hanger is strong enough but

too short for a frame the insertion of a longer link E will render the device available to engage frames of disproportionate length.

Having thus described my invention, what I claim as new, and desire to secure by Letters Patent, is—

1. A frame-hanger comprised of two furcated clasps having hooks on the ends of their limbs which will engage projections from the 10 rear side of a frame, a spring and a link intermediate of the clasps and loosely connected thereto, a prop-piece loosely secured to one clasp and adapted to project at an angle therefrom, and a hanging cord or wire strand, substantially as set forth.

2. In a frame-hanger, the combination, with a furcated clasp having hooks on the ends of its limbs, which limbs are provided with series of ratchet-teeth, a spiral spring on the 20 lower end of this clasp, a lower furcated clasp having hooks on the ends of its limbs, and a link between the clasps, of a prop-piece loosely

secured to the upper clasp and adapted to diverge therefrom, a brace jointed to the prop-piece and engaging the teeth on the limbs, 25 and a hanger wire or cord attached by its ends to the limbs of the upper clasp, substantially as set forth.

3. The combination, with a frame having projections on its rear side, of a hanger therefor comprised of a clasp having two limbs which are serrated and have hooks on their ends, a spring on the clasp, a link on the spring, a lower clasp on the link having limbs with hooks on their ends, a stay-bar on the upper 35 clasp, a prop-piece on the stay-bar, a rocking brace on the prop-piece which engages with the serrations of the clasp-limbs, and a hanger cord or wire on the limbs of the upper clasp, substantially as set forth.

DAVID G. RULON.
